UNITED STATES PATENT OFFICE.

JOHN M. KLEIN, OF CHICAGO, ILLINOIS.

WIRE CLAMP OR STRETCHER.

1,184,106.

Specification of Letters Patent. Patented May 23, 1916.

Application filed May 21, 1910. Serial No. 562,603.

To all whom it may concern:

Be it known that I, JOHN M. KLEIN, a citizen of the United States, and a resident of the city of Chicago, county of Cook, and

5 State of Illinois, have invented certain new and useful Improvements in Wire Clamps or Stretchers, of which I do declare the following to be a full, clear, and exact description, reference being had to the accompanying drawing, forming a part hereof.

The present invention has relation to that class of wire clamps or stretchers commonly employed by linemen in the stringing of telephone, telegraph or like wires, an example of this type of stretcher being illustrated in Letters Patent of the United States No. 800,745, granted to me October 3, 1905.

The present invention has for its object to improve the construction of clamp so that 20 it will securely hold the wire and so that the interference of the clamp with the wire, when joints are to be made, will be avoided.

The invention consists in the features of novelty hereinafter described, illustrated in 25 the accompanying drawing and particularly pointed out in the claims at the end of this specification.

Figure 1 is a view in side elevation of a clamp embodying my invention. Fig. 2 is a similar view with the jaws shown in open 30 position. Fig. 3 is a view in longitudinal section on line 3—3 of Fig. 1. Fig. 4 is a view in cross section on line 4—4 of Fig. 1. Fig. 5 is a view in cross section on line 5—5 35 of Fig. 1.

As shown, the body of the clamp A is provided with an offset jaw A' that is preferably formed integral with the body. Through this offset or rigid jaw A' passes 40 a headed bolt or rivet 2 to which is pivotally connected one end of a lever B. Through this lever B passes a headed bolt or rivet 3 that passes through the movable jaw C of the clamp. The outer end of the lever B 45 has pivotally connected thereto, by a bolt 4, the parallel links D, one of said links being upon each side of the lever B, and through the opposite ends of these links D passes a bolt or rivet 5 that also passes through a slot a in the body A, and upon the outer 50 ends of this rivet 5 are pivotally mounted the ends of a swivel loop or coupling E. The body A is also formed with an inclined slot a' above the jaw A' and through this slot 55 passes a headed pin or rivet 6 that passes also through the movable jaw C and serves

to guide this jaw C in its movements so that, as it moves away from the rigid jaw A', it will maintain a substantially parallel relation thereto.

Between the links D and mounted upon a bolt or stud 7 is a coil spring F, one end of which spring bears against a stop-pin 8 that projects inward from one of the links D, while the other end of the spring F bears 65 against a shoulder b adjacent the upper end of the link D. The effect of the spring F is to force the movable jaw C normally to its closed position.

With wire clamps or stretchers of the 70 character described, as heretofore constructed, it has been found that, if the opposing faces of the fixed and movable jaws between which the wire is clamped be smooth, there is danger of the slipping of the wire, notwithstanding the pressure thereon of the jaws. It has been heretofore proposed to remedy this objection by forming teeth or serrations upon the jaws. But this has proved objectionable because of the cutting 75 of the wire or of the insulating covering surrounding the same. I have found that the slipping of the wire through the jaws can be most effectively prevented and at the same 80 time the cutting of the wire or its insulating 85 covering can be avoided by forming the working face of one of the jaws with a series of plain surfaces or section c interspaced one from another by transverse grooves c'. In the preferred form of the invention, the 90 grooves c', are of varying depth, being shallower or vanishing at the outer side of the jaw C and being of greatest depth at the inner side of said jaw. Preferably also the 95 working faces of both jaws are provided with longitudinal grooves for receiving the wire.

In practice it is found that, when a wire is placed between the jaws A' and C, the short, plain surfaces of the jaw C, separated 100 as they are by the spaces c', will most effectively grip the wire, so that it cannot slip through the jaws, and yet the length of the surfaces c' is such that they are prevented from injuring the surface of the wire or of its insulating coating, as would be the case if the surfaces of the jaw were simply serrated.

By forming one at least of the working 110 faces of the jaws with a series of transverse grooves and dividing said working face into a series of short plain sections (that is to

say, short sections having practically smooth faces to engage the wire), the danger of injury of the wire or its coating is guarded against.

5 The spaces c' can be readily cleaned when they become clogged. Inasmuch as the spaces c' (in the preferred form of the invention) do not cut through the jaw C at its outer face, the slipping of the wire into the 10 jaw is more readily effected than would be the case if the spaces c' extended of uniform depth from side to side of the jaw C.

When the jaws are to be opened for the 15 purpose of inserting a wire, it is only necessary to move inward the link or coupling E until the jaws occupy the open position seen in Fig. 2 of the drawing.

In prior forms of clamps or stretchers, it 20 has been customary to provide a pivoted link or coupling similar to the link or coupling E hereinbefore described, but with such prior clamps the coupling has been free to swing in either direction around the pivot bolt or rivet that connected it to the body of the 25 clamp. In practice, this free movement of the link or coupling has been found objectionable because, when it swings across a line drawn between the opposing faces of the 30 jaws, it interferes with the insertion of the wire in the jaws. This is a serious objection, as the lineman, when using the clamp, as in stringing telegraph or telephone wires, must frequently manipulate the stretcher with one hand, while he uses the other in maintaining 35 his position upon the pole. To overcome this objection, I have provided means whereby the swinging of the link or coupling E across a line parallel with the opposing faces of the jaws shall be prevented. In 40 the preferred form of my invention, a stop

G is formed at the end of one of the links D, this stop extending into the path of the link or coupling E, so as to limit its downward movement. By preference, this stop 45 G is formed integral with the end of the link D by merely turning outward the end of the link, as clearly shown in Fig. 5 of the drawing. I do not wish the invention, however, in its broader scope, to be understood as restricted to this specific form of stop for 50 limiting the movement of the link or coupling E, as other means may be employed for effecting such result.

Having thus described my invention, what I claim as new, and desire to secure by Letters Patent, is:—

1. A wire clamp adapted for lateral insertion of the article to be clamped and comprising oppositely disposed jaws, one at least of said jaws being formed of short plain 60 gripping faces with spaces between said faces, said spaces being closed at the insertion side of the jaws, and being open and relatively deep at the opposite side of said jaws, whereby the article to be clamped will 65 be drawn more tightly into said jaws and prevented from slipping out thereof.

2. A wire clamp, comprising oppositely disposed jaws, means for operating said jaws comprising a connecting portion, and a 70 coupling pivoted to said portion, said portion having an integral extension adjacent said pivot and projecting into the path of said coupling and serving to prevent the swinging of said coupling across a line 75 parallel with the opposing faces of the jaws.

JOHN M. KLEIN.
